UNITED STATES PATENT OFFICE.

CHARLES H. NORTON, OF WORCESTER, MASSACHUSETTS, ASSIGNOR TO NORTON COMPANY, OF WORCESTER, MASSACHUSETTS, A CORPORATION OF MASSACHUSETTS.

STEADY REST.

Application filed January 5, 1921. Serial No. 435,097.

To all whom it may concern:

Be it known that I, CHARLES H. NORTON, a citizen of the United States of America, residing at Worcester, in the county of Worcester and State of Massachusetts, have invented certain new and useful Improvements in Steady Rests, of which the following is a full, clear, and exact specification.

My invention relates to a steady rest, and more particularly to an automatic indicating steady rest for supporting the rotating work and indicating the extent of the grinding operation.

In accordance with previous theories of grinding, steady rests have been constructed to support rotating cylindrical work not only on the lower side toward the grinding wheel but also on the side opposite the wheel whereby the rest shoe will be fed forward to hold the work firmly against the wheel, and in the usual practice of grinding the operator has constantly adjusted screw feeding members to force the steady rest shoe into contact with the work. As a result, if the work is crowded too much into the wheel, there is a tendency for chattering to take place until the wheel has ground itself out, this vibratory motion being up and down as well as into the wheel. It is accordingly an object of my invention to prevent vibration or chattering of the work by applying a force thereto which acts to hold the work away from the wheel and so making it impossible to feed the work into the wheel during grinding by adjustment of the steady rest.

The desirability of an automatically feeding steady rest has long been recognized and numerous attempts have been made to provide a spring pressed rest shoe which will be held against the work with a constant pressure. However, due to the fact that vibration has not been eliminated, the spring and the relatively light movable parts of the steady rest have formed sources of vibration and so have required the use of positive means for limiting the movement of the steady rest shoe. It is accordingly a further object of my invention to provide a steady rest with a massive shoe and an automatic mechanism which will keep the shoe in close contact with the work as grinding proceeds and so utilize the mass of the steady rest to aid in damping vibrations.

Furthermore, the operation of grinding is

ordinarily hindered by the necessity for the operator to caliper the work at intervals, which usually requires stopping the process and in certain cases removing the steady rest shoe from adjacent the work in order to get at the latter. It is accordingly a still further object of my invention to provide an automatic self-indicating steady rest which will indicate the extent to which grinding has proceeded and which in conjunction with the usual wheel cross feed mechanism may be employed to grind to a predetermined size and, except for wheel wear for which compensation may be made, automatically stop grinding when the operation has proceeded to a certain definite stage. A minor object related to the above is to provide a shoe supporting construction which may be readily swung away from the work at a point opposite the grinding wheel for any caliper that may be considered necessary to confirm the results indicated by a dial on the steady rest.

With these specific objects in view, it is a broad object of my invention to provide a steady rest which will make it feasible for the work to traverse relative to the wheel at a speed heretofore not obtained in a grinding machine of this type, due to the necessity for the operator to be constantly adjusting the numerous steady rests required to support a long piece of cylindrical work, and thus to render the process of grinding rapid and economical and to produce uniform results in production grinding where it is desired to duplicate closely a piece of work previously ground to a required size.

With these and other objects in view, as will appear from the disclosure herein set forth, my invention resides in the combination of parts described in the specification and covered by the claims appended thereto.

In the drawings, in which like reference characters indicate like parts:

Figure 1 is a perspective view of my improved steady rest, part of the spring housing being broken away;

Fig. 2 is a rear elevation thereof;

Fig. 3 is a section thereof, parts being shown in elevation, indicating the manner of its connection to the grinding machine table and the relation of the work to the work shoe at the beginning of the grinding operation;

Fig. 4 is a view similar to Fig. 3 of the forward portion of the steady rest, showing the relation of the work to the shoe at the finish of the grinding operation;

5 Fig. 5 is an end view showing the manner of mounting of the work shoe on the shoe carrier of the steady rest; and

10 Fig. 6 is a cross section through the spring housing showing the means for adjusting the tension of the spring.

In accordance with my invention, I propose to steady cylindrical work during rotation only on its front side, or on that side which is toward the grinding wheel, 15 and below the line of thrust and to move the steady shoe toward the work axis as grinding proceeds, so that in the normal use of my steady rest the work cannot be fed into the wheel during grinding by 20 means of the steady rest shoe. This will render it impossible for the work to vibrate during grinding, since the shoe being located on the lower forward side is so positioned that the wheel thrust tends to move the work along the shoe and away from the wheel. Furthermore, I insure damping the 25 work vibrations by utilizing a massive shoe carrier and maintaining the shoe in contact with the work with sufficient pressure 30 to move the shoe forward as grinding proceeds, but not enough pressure to affect the grinding detrimentally, whereby the shoe carrier, being massive and having considerably inertia as well as having a different 35 period of vibration from that of the work, will not yield to the vibratory impulses which the wheel would ordinarily produce.

A suitable construction for carrying out 40 this method may comprise a work-steadying shoe having a partial cylindrical surface of revolution which corresponds in radius with that of the desired radius of the finished work, whereby I may maintain contact between the shoe and the work only 45 adjacent the nose of the shoe nearest the wheel so that the curvature of the shoe will not fit the work until grinding has been completed. In order that the operation may be automatic, I may mount the shoe 50 on a massive support which is held in contact with the work by suitable mechanism, and I may furthermore provide an indicating device for registering the movement of the work shoe to give warning when grinding 55 has proceeded to a given stage. In conjunction with the indicator, it is desirable to provide a stopping device adapted to stop the shoe feed automatically.

60 In order that this invention may be more readily understood, reference is to be had to the accompanying drawings illustrating one embodiment of a steady rest utilizing the principles of my discovery. As there illustrated, I have shown my steady rest 65 as comprising a shoe carrier 1 supported

by and movable relative to a stand 2 fastened to a suitable part of the grinding machine table 3. In my preferred form this shoe carrier may take the form of a lever having a relatively massive arm 5 70 to which the work shoe is connected. The shoe carrying lever 1 I have shown pivoted at 8 to two lugs 9 extending forwardly from the body 2 and I provide means, such as a spring 10, for holding the shoe 6 against 75 the work at all times during a grinding operation. In the practice of my method the shoe may be fed manually by suitable mechanism, although I prefer to make my steady rest, after it is once adjusted, automatic in its action.

An important distinction between my improved steady rest and those heretofore used is illustrated by the manner in which the shoe bears against the work W during 80 the greater part of the grinding operation so as to exert a force thereon opposed to the downward thrust of the grinding wheel 7 and also tending to move the work away 85 from the grinding wheel. To allow of the proper adjustment of the shoe so that the force exerted on the work may be applied as above pointed out, I provide a work shoe 6, which I have shown as comprising two concentric bearing surfaces 13 and 14 of 90 equal radius forming a partial cylindrical surface of revolution. The radius of the curved bearing surfaces 13 and 14 is preferably substantially equal to the radius of the work when ground to size, as shown in 95 Fig. 4, and to minimize wear I may construct them of any suitable wear-resisting material, such as hardened steel. I may, moreover, utilize a shoe having a continuous curvature instead of the two curved 100 bearing surfaces shown.

The work shoe is mounted on a shoe holder 15 loosely pivoted adjacent its upper end by means of the screw 16. A spring 17 is arranged between the head of this screw 110 and a shoulder 18 formed by a countersink in the shoe holder, this spring thus serving to press the upper end of the holder toward the lever 1. At its lower end this shoe holder is formed at the middle with a bearing lug 21 and is tapered from this lug to the sides, as shown in Fig. 5. The purpose of this arrangement is to allow lateral rocking of the shoe holder so that the shoe 6, which may be of substantial width, may 115 align itself accurately with the work. The shoe is held clamped on the holder between a shoulder 22 and the set screw 23 in the usual manner to allow of the substitution of different sized shoes to fit the work. In 120 order to tip the shoe 6 away from and toward the wheel around the bearing lug 21 as a pivot, I provide a set screw 24 (Fig. 3). The spring 17 coacts with this set screw to hold the shoe holder in any adjusted 125 130

position. In order to properly adjust the shoe, a piece of work is first ground to the desired size when supported between centers and the steady rest shoe is then brought up 5 against the work and its angular position adjusted by means of the screw 24 until its bearing surfaces fit the work, as shown in Fig. 4.

From this construction it will be obvious, 10 by reference to Fig. 3, that when a piece of work to be ground which, let us say, is .005" oversize, is first placed in the machine and the shoe 6 is brought up against the work, it will have only a substantially line contact 15 with the work at a point below the work and adjacent the wheel and the work will be entirely unsupported by the bearing surface opposite the wheel until the work is 20 ground to size, so that there is no chance whatsoever of the work being crowded into the wheel with the attendant objectionable features.

As a means for connecting the spring 10 with the lever 1, I have shown the arm 11 of 25 the lever 1 provided with a gear sector 26 meshing with a gear sector 27 rigidly secured to the shaft 28 extending transversely of the body or stand 2. One end of this 30 shaft extends outside the body casing where it is rigidly connected to one end of the spiral spring 10, the other end of the spring being connected to a spring housing 29 which is rotatably mounted on the annular 35 stud 30 and can be locked in position by a set screw 31. The spring 10 can by this means be suitably tensioned to hold the shoe 40 in contact with the work so that the massive shoe carrier may damp the vibrations, the actual pressure of the spring being determined by the nature of the work, the conditions of grinding and the accuracy in 45 results desired. The stud 30 is provided with a plurality of holes 32, any one of which can be engaged by the set screw 31 when the housing 28 is turned by a suitable tool, such as a spanner wrench, to align these parts.

In order to require as little attention on 50 the part of the operator as possible, I provide a stop for limiting the forward motion of the shoe carrying lever 1 and this may take the form of a set screw 33 mounted in a lug 34 projecting rearwardly from the body 2 and provided with the usual lock 55 nut 35. I have shown the inner end of this screw 33 located in the path of an arm 36 which may be made integral with the sleeve carrying the gear sector 27. By the use of 60 this stop the finishing cuts will be made with the bearing surfaces on the shoe 6 simply engaging the surface of the work without exerting pressure thereon.

Another important feature of my invention 65 is the provision of indicating means on the steady rest to tell the operator at a glance when the work is ground to size, or

to indicate the wear of the wheel where a positive stop is employed in the cross-feed mechanism. Any suitable indicator for showing small variations in size may be employed, but I have illustrated an Ames 70 dial indicator 37 suitably mounted on a bracket 38 at the rear of the rest body 2 and operatively connected to the shaft 28 by any suitable means, such as the arm 39 rigidly connected to the end of the shaft and a lever 75 40 connected as by means of a screw 41 to the bracket 38. The arm 39 acts on the relatively short arm of the lever 40, while the long arm of said lever cooperates with the movable spring pressed plunger 44 of 80 the indicator, the motion of the plunger being communicated to the hand on a dial by a rack and pinion mechanism, as is well known. It will be seen from this construction that any movement of the shoe 6 is 85 greatly magnified on the hand on the indicator. The lever 40 has a very limited swinging movement and since any lost motion between it and its connecting screw 41 would result in inaccuracies in the reading on the 90 dial indicator if the lever were pivoted about the screw, I pivot the lever on the knife edge 42 against which it is held by a light spring 43, and to permit such pivotal movement about the knife edge, I make 95 the screw 41 slightly smaller than the hole in the lever 40. A set screw 45 limits the swing of the lever 40 in one direction, and this is preferably adjusted so as to allow less than one complete revolution of the 100 hand on the indicator.

I so arrange the relative positions of the dial and the hand of the indicator that the hand will point to zero on the scale when the arm 36 is up against the stop screw 33 105 and the work is ground to size. I prefer to use some kind of indicator, so that my steady rest will be a precise instrument for producing duplicate work, and to avoid any difficulty which the operator might otherwise meet in attempting to ascertain 110 whether the arm 36 was up against the stop screw 33. The dial of the indicator is preferably graduated in thousandths of an inch, although any suitable graduation may be 115 utilized, and in grinding operations of this sort where successive pieces are ground to duplicate sizes, the cross-feed mechanism is provided with a positive stop to limit movement of the wheel into the work. If there 120 has been appreciable wheel wear, when the wheel feed mechanism has reached the stop, the work will be oversize. As a consequence, the hand on the dial indicator will not be turned to zero and the operator can 125 read directly the amount of wheel wear and then feed the wheel the indicated amount by the usual micrometer feed adjustment and thus bring the work to the desired size and the indicator to zero.

In order that the operator may measure certain types of work, such as crank pins, I provide a construction which permits swinging the shoe away from the work readily and for holding it in this position. The means for accomplishing this may comprise a handle 46 on the arm 36 and a spring pressed latch 46 pivoted thereto, the latch being lifted when the handle is swung downwardly 10 by a cam surface 47 and when the handle is down it automatically engages in a notch or opening 48 on the body 2 of the rest. To lower the shoe 6 and hold it in lowered position, the operator merely presses on the handle until the latch engages the notch. The latch is released to allow the spring 10 to return the shoe by pressing it toward the handle.

To clamp the steady rest to the work 20 table, I may employ any suitable means such as the clamping means 50 which is substantially the same as that shown and described in the patent to Wilcox et al No. 1,214,629 dated Feb. 6, 1917.

25 It will be seen from the foregoing disclosure that I have produced an exceedingly fine precision device in the form of an indicating steady rest for producing duplicate work with a minimum of attention 30 from the operator and which, because of the manner in which it supports the work, causes a minimum of wheel wear and avoids vibration of the work, thereby increasing production and the life and efficiency of the 35 grinding machine on which it is used.

It is obvious that changes may be made 40 in the specific construction of my device and that equivalent elements may be substituted for the parts herein disclosed without departing from the scope of my invention as expressed in the claims appended hereto.

Having thus described my invention, what I claim as new and desire to secure by Letters Patent is:

45 1. A steady rest for grinding machines comprising a stand, a member movably mounted on said stand which is arranged to serve as the sole steadyng support for the work during grinding, and means to move said member and apply pressure on the front side only of the work and thereby tend to hold the work away from the wheel and prevent vibrations.

50 2. A grinding machine steady rest for producing cylindrical work comprising a supporting stand adapted to be mounted on the machine, a relatively massive work support movably mounted on the stand and having a work-engaging surface thereon, and means for automatically moving said support and holding it in contact with the front side only of the work during the initial grinding operation, whereby vibrations 55 of the work may be damped by the inertia 60 of the support.

3. A grinding machine steady rest for producing cylindrical work of a given size comprising a supporting stand, a work-engaging shoe movably mounted on said stand for initial engagement only with that side 70 of the work which is toward the grinding wheel, means including a massive body to maintain contact of said shoe with the work and damp vibration thereof, and means to render said shoe incapable of bearing 75 against the work on the side thereof which is opposite the wheel before the work has been ground to the required size.

4. A grinding machine steady rest for producing cylindrical work of a given size 80 comprising a supporting stand adapted to be mounted on the grinding machine, a work shoe movably mounted on said stand and having a partial cylindrical surface, the radius of which is substantially equal to that 85 desired for the finished work, means to hold said shoe in a line contact with the work on that side thereof which is toward the grinding wheel and below the line of contact between the wheel and the work, said 90 means being capable of moving the work shoe, as grinding proceeds, to a position in which the work substantially fits the curvature of the shoe, whereupon the grinding operation is completed.

95 5. A steady rest for grinding machines comprising a stand, a relatively massive shoe carrier pivotally mounted thereon, a work-engaging shoe on said carrier having a partial cylindrical surface, the radius of which 100 is equal to that of the finished work, and means for automatically applying a substantially uniform pressure to said carrier to hold said shoe against that side only of the work which is adjacent the wheel during substantially the entire grinding operation and to move the shoe toward the work axis as grinding proceeds until the cylindrical surface of the shoe is in contact with the work at the completion of the grinding 110 operation.

115 6. A grinding machine steady rest for producing cylindrical work comprising a stand adapted to be supported on the grinding machine, a relatively massive shoe carrier pivotally mounted thereon for an upward rocking movement, a work-engaging shoe on said carrier which is arranged to serve as the sole steadyng support for the work, and automatic means for exerting 120 pressure against said carrier to hold said shoe in engagement with that side only of the work which is toward the grinding wheel and below the line of contact between the wheel and the work, whereby vibration of 125 the work is damped.

130 7. A grinding machine steady rest comprising a stand adapted to be mounted on the grinding machine, a work-steadying member pivotally mounted on said stand,

and means for moving said member and holding it against the work during the grinding operation, comprising a shaft, a spring tending to rotate said shaft, and driving connections between said shaft and member.

8. A grinding machine steady rest for producing cylindrical work comprising a stand adapted to be mounted on the grinding machine, a relatively massive lever pivoted thereon, a work shoe mounted thereon, a gear sector on said lever, a gear on the stand engaging said sector, and a spring connected with said gear to swing the work shoe into engagement with the work.

9. A grinding machine steady rest comprising a stand adapted to be mounted on the grinding machine, a work-steadying shoe movably mounted on said stand, said shoe having a partial cylindrical surface, the radius of curvature of which is equal to that of the finished work, means to adjustably position said shoe so that it will initially contact with the work on that side only which is adjacent the grinding wheel, and means for feeding the shoe as grinding proceeds so as to support the work only on the side towards the grinding wheel until the curvature of the work fits the curvature of the shoe.

10. A grinding machine steady rest comprising a stand adapted to be supported on the grinding machine, a shoe carrier movably mounted on said stand, a shoe adjustably mounted on said carrier, said shoe having a partial cylindrical surface adapted to bear against the work, and means providing a rocking support between the shoe and carrier whereby the shoe may be automatically aligned with the axis of the work by engagement with its periphery.

11. A grinding machine steady rest comprising a stand adapted to be supported on the machine, a shoe carrier movably mounted on said stand, a shoe having a work supporting surface, adjustable means to locate said shoe on the carrier so that the shoe may contact only with the front side of the work and means to move the carrier in such a direction that the shoe will support the work only on its front side as grinding proceeds.

12. A grinding machine steady rest for producing cylindrical work comprising a shoe carrier movably mounted on said stand, a work-engaging shoe of substantial width movably mounted on said carrier, said shoe having a partial cylindrical surface whose radius is substantially equal to the radius of the finished work, means for moving and holding said shoe against the work, and means providing a universal rocking support between the shoe and carrier whereby the shoe can be rocked to align it with the work axis and also to cause the cylindrical

surface to fit the work at the completion of the grinding operation.

13. A grinding machine steady rest for producing cylindrical work comprising a stand, a work-steadying member movably mounted on said stand, means for moving said member and holding it against the work during the grinding operation, and precision means for indicating to the operator when the work has been ground to the desired size.

14. A grinding machine steady rest comprising a stand adapted to be mounted on the grinding machine, a work-steadying member movably mounted on said stand, means for moving said member and holding it against the work during the grinding operation, and means cooperating with said member comprising an indicator to inform the operator of the amount of wheel wear.

15. A grinding machine steady rest comprising a stand adapted to be mounted on the grinding machine, a work-steadying member pivotally mounted on said stand, means for moving said member and holding it against the work during the grinding operation, and precision means on said stand cooperating with said member for indicating to the operator when the work has been ground to the desired size, comprising a dial indicator and movement magnifying means between said member and the indicator.

16. A grinding machine steady rest for producing cylindrical work of a given size comprising a stand, a work-steadying shoe movably mounted on said stand, means for moving said shoe and holding it against the work during the grinding operation, means for stopping the movement of the shoe at a predetermined point, and precision means to register the movement of the shoe and indicate when it approaches this point.

17. A grinding machine steady rest for producing cylindrical work comprising a stand adapted to be supported on the grinding machine, a relatively massive shoe carrier pivotally mounted thereon, a work shoe having a partial cylindrical surface, the radius of which is equal to that of the finished work, said shoe being adjustably mounted on said carrier to engage that side only of the work which is adjacent the grinding wheel, a spring operated means for supplying pressure to said carrier to hold said shoe against the work and move the shoe forward until its cylindrical surface is in contact with the work at the completion of the grinding operation, and a precision means to register movement of the shoe and indicate when the work has been ground to size.

18. A grinding machine steady rest comprising a stand adapted to be mounted on the grinding machine, a work-steadying shoe

movably mounted on said stand, means for feeding the shoe forward as grinding proceeds, and means for effecting a quick movement of the shoe away from the work to permit caliperizing thereof at a point opposite the shoe, said means permitting automatic return of the shoe to its former steadyng position.

19. A grinding machine steady rest comprising a stand adapted to be mounted on the grinding machine, a work-steadying shoe movably mounted on said stand, means for

moving the shoe as the grinding proceeds so as to support the work only on the side toward the grinding wheel, means for readily moving the shoe away from the work a distance sufficient to permit caliperizing the work at a point opposite the shoe, and means for automatically returning and locating the shoe in its initial position.

Signed at Worcester, Massachusetts, this 31st day of Dec., 1920.

CHARLES H. NORTON.
